(57) **CLAIM**

The ornamental design for an archery bow grip, as shown and described.

DESCRIPTION

FIG. 1 is a perspective view of a first (e.g. right-handed) embodiment of the archery bow grip.

FIG. 2 is a front view of the first (e.g. right-handed) embodiment of the archery bow grip.

FIG. 3 is a rear view of the first (e.g. right-handed) embodiment of the archery bow grip.

FIG. 4 is a left side view of the first (e.g. right-handed) embodiment of the archery bow grip.

FIG. 5 is a right side view of the first (e.g. right-handed) embodiment of the archery bow grip.

FIG. 6 is a top view of the first (e.g. right-handed) embodiment of the archery bow grip.

FIG. 7 is a bottom view of the first (e.g. right-handed) embodiment of the archery bow grip.

FIG. 8 is a perspective view of a second (e.g. left-handed) embodiment of the archery bow grip.

FIG. 9 is a front view of the second (e.g. left-handed) embodiment of the archery bow grip.

FIG. 10 is a rear view of the second (e.g. left-handed) embodiment of the archery bow grip.

FIG. 11 is a right side view of the second (e.g. left-handed) embodiment of the archery bow grip.

FIG. 12 is a left side view of the second (e.g. left-handed) embodiment of the archery bow grip.

FIG. 13 is a top view of the second (e.g. left-handed) embodiment of the archery bow grip; and,

FIG. 14 is a bottom view of the second (e.g. left-handed) embodiment of the archery bow grip.

The broken lines depict portions of the archery bow grip that form no part of the claimed design.
